ROPE GUARD FOR PAPER MAKING MACHINES

Russell Carpenter, Wayagamack Island, Three Rivers, Quebec, Canada

Application November 1, 1935, Serial No. 47,883
In Canada November 3, 1934

5 Claims. (Cl. 34—48)

This invention relates to rope guards for preventing accidental displacement and breakage of the carrier ropes associated with the dryer rolls of a Fourdrinier paper making machine. 5 More particularly, the invention relates to improvements in rope guards of the kind disclosed in my prior United States Patent No. 1,660,917, granted Feb. 28, 1928.

One object of the present invention is to prevent rope displacement due to accumulation of wads of broken paper between opposing grooved portions of adjacent dryer rolls contained in the same row and is achieved by providing the guards with deflectors whereby wads of broken paper thrown or carried towards the ropes are intercepted and deflected back towards the central portions of the dryer rolls.

Another object is to prevent rope displacement resulting from wads or other accumulations of broken paper being carried around in the roll grooves and being caught beneath the ropes as they enter said grooves. This object is achieved by providing the guards with wall portions arranged to overlie and obstruct portions of the dryer roll grooves located immediately in advance of the points of entry of the rolls.

Another object is the provision of rope guards constructed to completely enclose the ropes so that it is impossible for wads or other accumulations of broken paper to engage the ropes at or immediately in advance of the points of entry of the ropes into the dryer roll grooves.

Other objects and advantages of the invention, as well as the details of construction, will be more readily understood from the following detailed description, taken in connection with the accompanying drawings, in which

Fig. 1 is a diagrammatic view of a portion 40 of the dryer section of a Fourdrinier paper making machine equipped with guards constructed and applied in accordance with my invention.

Fig. 2 is a fragmentary sectional view along the line 2—2 of Fig. 1.

45 Fig. 3 is a rear elevation of one of the guards as it appears in place on a dryer roll.

Fig. 4 is a front elevation of one of the guards as it appears in place on a dryer roll.

Fig. 5 is a perspective view of the guard appearing in the preceding figures.

Fig. 6 is a perspective view of a modified form of guard.

Fig. 7 is a view, in side elevation, of a dryer roll equipped with a guard constructed as disclosed in Fig. 6.

Fig. 8 is a front elevation of the roll and guard assembly appearing in Fig. 7.

Fig. 9 is a bottom plan view of the guard appearing in Figs. 7 and 8.

Fig. 10 is a view looking towards one end of the guard appearing in Figs. 7 and 8.

Fig. 11 is a view looking towards the opposite end of the guard appearing in Figs. 7 and 8.

Fig. 12 is a perspective view of a slight modification of the guard appearing in Figs. 6 to 10 inclusive.

In Fig. 1 of the drawings, I have shown a portion of a conventional Fourdrinier dryer section including the frame structure 5, the dryer rolls 6 and the carrier ropes 7, the latter running in peripheral grooves 8 formed in the dryer rolls adjacent their front ends. According to the present invention each dryer roll is equipped with a rope guard 9 arranged adjacent the point where the ropes enter the groove 8.

The guard shown in Figs. 2 to 5 inclusive comprises a channel-shaped member presenting a front wall 10 and side walls 11 and 12. The front wall 10 lies perpendicular to the periphery of the roll immediately in front of the groove 8 and is made of gradually diminishing width toward the point where the ropes enter the groove. The side walls 11 and 12 project rearwardly over the groove 8 to form a channel in which the ropes are received and held against undue displacement. The side wall 11 and the lower edge of the front wall 10 lie close to the periphery of the dryer roll and have approximately the same curvature.

Due to the varying width of the front wall 10, the side wall 12 is disposed at such a tangent to the dryer roll that the distance between this wall and the periphery of the dryer roll gradually diminishes to a relatively small clearance at the end of the wall nearest the point where the ropes enter the groove 8.

As shown more particularly in Fig. 2, the side wall 12 gradually increases in width toward the end nearest the point of entry of the ropes into the groove 8. A deflector flange 13, formed integral with the free longitudinal edge of this wall, is thus disposed at an oblique angle to the longitudinal axis of the dryer roll so that wads of paper coming in contact with the deflector will be deflected toward the center of the roll.

It will also be observed that the side wall 11 of each guard is shorter than the walls 10 and 12 and is disposed to cover the rope groove 8 for a short distance in advance of the point of entry of the ropes. One end of wall 11 ter-

minates at the entrance end of the rope receiving channel of the guard and is provided with a lug 14 projecting into the groove 8. The other end of wall 11 terminates at a point intermediate the length of the walls 10 and 12 and is preferably bevelled as indicated at 11a.

Each of the guards described in the foregoing is supported from the frame 5 by means of a bracket 15 which may be attached to the frame 10 and guard in any suitable manner. As here shown one end of the bracket is removably fastened to the frame by bolts 16 or other suitable fastening means. The other end of the bracket is fastened to the guard by a bolt 17 having its head and shank portions fitted in a T-shaped slot 18 formed in an integral projection or lug 19 of the guard. When the bolt 16 is loosened the slot 17 permits the guard to be adjusted on the bracket 15.

20 When dryer rolls are equipped with guards constructed and applied as herein described, there is no danger of the ropes leaving the dryer roll grooves and becoming entangled with the frame or other parts of the dryer since 25 lateral displacement of the ropes toward the front end of the rolls is prevented by the front guard wall 10 while undue radial displacement of the ropes is prevented by the overlying guard wall 12 which approaches close to the periphery 30 of the roll at the point where the ropes enter the groove. The housing of the ropes in the channel formed by the guard walls 10, 11, and 12 is another factor in preventing rope displacement since it makes it more difficult for wads or other 35 accumulations of broken paper to become entangled with the ropes as they enter the dryer roll groove. The provision of the inclined deflector 13 is also an important feature. In the absence of this deflector wads or other accumulations of paper thrown forwardly against the guards may sometimes be carried past the guards and caught between the rope carrying grooves of adjacent dryer rolls contained in the same row. When this happens the ropes are frequently forced out of the grooves by the pressure of the wads caught between the rolls. The deflector 13 prevents this by deflecting the wads of paper away from the ropes and toward the central portions of the roll.

50 The arrangement of the guard wall 11 and its lug 14 to cover and obstruct the groove 8 immediately in advance of the point of entry of the ropes also has a definite advantage. It prevents wads or other accumulations of paper 55 (entering the roll groove in advance of the guard) being caught beneath the ropes as they enter the groove. Lug 14 is made narrower than groove 8 to permit endwise play of the roll.

The modification appearing in Figs. 6 to 11 60 inclusive, affords a rope guard which completely encloses the portions of the ropes passing therethrough. In this case the side walls 12 of the guard are divided into two sections designated 12a and 12b, the former being integral with the 65 upper edge of the front wall 10 and the latter being hinged to the upper edge of the front wall as indicated at 20. A rear wall 21 and an end wall 22 are formed integral with the hinged side wall section 12b. When the parts are arranged as shown in Figs. 7 to 11 inclusive the rear side of the rope passage through the guard is closed off by the rear wall 21 while the mouth of the passage is substantially closed by the end wall 22 in which a slot 23 is formed for the 75 passage of the ropes. Intermediate its length

the rear wall 21 is provided with an offset portion 25 affording an inclined deflecting surface 26 which takes the place of the previously described deflector 13. A lever extension 26, formed integral with the hinged side wall section 12b, is adapted to be connected with any suitable operating mechanism for swinging the walls 21 and 22 to the position shown in Fig. 6 so that the guard may be readily opened when the ropes are being used to guide the paper through the dryer or when opening of the guard is desired to permit removal of the ropes.

When the carrier ropes 1 are being used to guide the paper over the dryer rolls (when starting up a machine or after a break in the paper sheet) the guard is opened by swinging walls 12b, 21 and 22 to the position shown in Fig. 6 to permit free passage of the paper web through the rope receiving channel of the guard. In this open position of the guard the ropes are 20 prevented from jumping the roll grooves by the overhanging side wall section 12a that is integral with the front wall 10. When the paper guiding operation is complete the guard is closed as illustrated in Figs. 7 to 11 inclusive so that 25 it completely encircles the ropes adjacent their point of entry into the roll groove.

In Fig. 12 I have shown a cylinder and piston device for controlling the opening and closing of the guard. As here shown the lever extension 30 is secured by a pivot connection 27 to a cylinder 28. A piston 29, working in the cylinder 28, is connected by its piston rod 30 to an arm 31 projecting outwardly from the guard wall 10. Air is admitted to and withdrawn from the lower end of the cylinder through a port 31 adapted to be connected with a suitable header (not shown). This header is equipped with a three-way valve for placing it in communication with a source of pressure or with an exhaust 40 opening.

Having thus described my invention, what I claim is:—

1. In a Fourdrinier paper making machine the combination of a rotary drying roll having a 45 peripheral groove, carrier ropes arranged to run in said groove and a rope guard presenting a rope receiving channel overlying the groove immediately in advance of the point where the ropes enter said groove, said guard comprising a front wall lying perpendicular to the periphery of the roll immediately in front of said groove and side walls projecting rearwardly over the groove to form the rope receiving channel.

2. In a paper making machine the combination of a rotary dryer roll having a peripheral groove, carrier ropes arranged to run in said groove, and a rope guard for preventing displacement of the ropes from said groove, said guard comprising a front wall lying perpendicular to the periphery of the roll immediately in front of the groove and side walls projecting rearwardly over the groove to form a channel in which the ropes are received and held against displacement from the groove, said front wall gradually diminishing in width toward the point where the ropes enter the groove.

3. In a Fourdrinier paper making machine the combination of a dryer roll having a peripheral groove adjacent its front end, carrier ropes arranged to run in said groove and a rope guard arranged to prevent the carrier ropes leaving said groove, said guard comprising a front wall lying perpendicular to the periphery of the roll immediately in front of the groove, and side 75

- walls projecting rearwardly over the groove to form a channel in which the ropes are received immediately in advance of their point of entry into the groove, the side wall of the channel 5 nearest the roll and the roll opposing edge of the front wall being positioned close to the periphery of the roll and having approximately the same curvature, the remaining side wall of the channel being provided, along its rearwardly 10 facing edge, with a deflector disposed at an oblique angle to the longitudinal axis of the roll so that wads of paper coming in contact with the deflector will be deflected towards the center of the roll.
- 15 4. In a Fourdrinier paper making machine the combination of a dryer roll having a peripheral groove, carrier ropes arranged to run in said groove and a rope guard completely encircling said ropes immediately in advance of their point 20 of entry into said groove, said guard comprising hingedly connected sections permitting the guard to be opened or closed.
5. In a Fourdrinier paper making machine the combination of a rotary drying roll having a peripheral groove, carrier ropes arranged to run in said groove, and a rope guard completely encircling said ropes immediately in advance of their point of entry into said groove, said guard comprising a front wall lying perpendicular to the periphery of the roll in front of said groove, side walls projecting rearwardly over said groove, a rear wall carried by the upper side wall, the last mentioned side wall being hingedly connected to the front wall and said rear wall being provided with an inclined rearward projection adapted to deflect wads or other accumulations of broken paper away from the ropes and toward the central portion of the roll. 10 15

RUSSELL CARPENTER. 20
